(57) **CLAIM**

The ornamental design for a frame sign, as shown and described.

DESCRIPTION

FIG. 1 is a top-left perspective view of a frame sign shown with larger top panel removed for clarity of disclosure; FIG. 2 is a top-right perspective view thereof; FIG. 3 is a top plan view thereof; FIG. 4 is a bottom plan view thereof; FIG. 5 is a right side elevation view thereof; FIG. 6 is a left side elevation view thereof; FIG. 7 is a front elevation view thereof; FIG. 8 is a back elevation view thereof; FIG. 9 is an enlarged detail view of portion 9 of FIG. 1; FIG. 10 is an enlarged detail view of portion 10 of FIG. 2; FIG. 11 is a top-left perspective view of a frame sign shown with the larger panel in a lifted position; FIG. 12 is a top plan view thereof; FIG. 13 is a bottom plan view thereof; FIG. 14 is a right side elevation view thereof; FIG. 15 is a left side elevation view thereof; FIG. 16 is a front elevation view thereof; FIG. 17 is a back elevation view thereof; FIG. 18 is a top-left perspective view of a frame sign; FIG. 19 is a top plan view thereof; FIG. 20 is a bottom plan view thereof; FIG. 21 is a right side elevation view thereof; FIG. 22 is a left side elevation view thereof; FIG. 23 is a front elevation view thereof; and, FIG. 24 is a back elevation view thereof.

The uniform broken lines show portions of the article that do not form part of the claimed design. The dash-dot-dash lines immediately adjacent the shaded areas define the bounds of the claimed design and form no part thereof.

1 Claim, 18 Drawing Sheets
